UNITED STATES PATENT OFFICE.

EDWIN F. GUTH AND RAYMOND V. OWEN, OF ST. LOUIS, MISSOURI, ASSIGNEES TO
LUMINOUS UNIT COMPANY, OF ST. LOUIS, MISSOURI, A CORPORATION OF MISSOURI.

LAMP HOLDER AND REFLECTOR.

1,172,522.

Specification of Letters Patent. Patented Feb. 22, 1916.

Application filed April 23, 1915. Serial No. 23,288.

To all whom it may concern:

Be it known that we, EDWIN F. GUTH and RAYMOND V. OWEN, citizens of the United States of America, residing at the city of 5 St. Louis, State of Missouri, have invented a certain new and useful Lamp Holder and Reflector, of which the following is such a full, clear, and exact description as will enable anyone skilled in the art to which it 10 appertains to make and use the same, reference being had to the accompanying drawings, forming part of this specification.

Our invention relates to a combined reflector and lamp supporting device, particularly suitable for street and factory service.

Its object is to secure a well insulated, ventilated and weather-proof construction comprising a minimum number of easily accessible parts.

20 In the accompanying drawings, which illustrate one embodiment of our invention, Figure 1 is a side view, partly in section and partly in elevation; Fig. 2 is a plan view of the upper end of the neck of the 25 reflector; and Fig. 3 is a bottom plan view of the reflector supporting stirrup.

1 represents a shade or reflector of insulating material, preferably vitreous china. The reflector is provided with a central 30 extension or neck portion as shown, and, extending across the neck portion and integral therewith is a socket carrying bridge 2 upon which the metal socket 3 is supported. The external diameter of the socket is less than 35 the interior diameter of the neck portion of the reflector and thus a ventilating passage is formed between the socket and reflector and through the openings 4 in the top thereof. The exterior of the neck portion 40 of the reflector is provided with an integral shoulder 5. The divided supporting stirrup 6, having the arms 7, is held in position around the neck of the reflector beneath the shoulder 5 by means of the 45 screws 8. The stirrup 6 may, of course, be otherwise supported than by the arms 7, these being shown merely as one suitable arrangement for this purpose. A cap 9 covers the top of the neck portion of the 50 reflector and rests upon the stirrup 6. It is held in position by lugs 10 on the arms 7, being capable of being sprung sufficiently to pass these lugs for application or removal. The diameter of the cap opening is greater

than the exterior diameter of the neck portion of the reflector thereby providing ventilating space, and through this space, the lead wires 11 are carried to the supply conductors. The lamp 12 may be surrounded by a bowl or shade 13, if desired. This shade 60 is also supported from the reflector, as shown.

The reflector and socket support being formed in one piece and of insulating material, the construction of the fixture is much 65 simplified since a single member serves as the necessary insulating portion of a lamp socket as well as a shade. This, in addition to the arrangement of the supporting stirrup coöperating with the integral shoulder 70 of the reflector and itself carrying the protecting cap, forms a complete fixture for the purposes described having very few parts.

We are aware of prior devices in which a lamp socket is positioned within the bell 75 or neck portion of a reflector, but these constructions do not possess the advantageous features of construction herein described.

Having fully described our invention, what we claim as new and desire to secure 80 by Letters-Patent of the United States is:

1. The combination of a reflector or shade of insulating material having a socket inclosing neck portion provided with a ventilating opening, and a metallic lamp socket 85 within the neck portion and supported by the reflector, the cross-sectional area of said socket being less than that of the interior of the neck portion of the reflector.

2. The combination of a reflector having 90 a hollow neck portion and an integral socket supporting bridge extending over the end thereof, and a metal lamp socket attached to said bridge, said socket having a smaller cross sectional area than the interior of the 95 neck portion of the reflector.

3. The combination of a reflector or shade of insulating material having a neck portion provided with an integral socket supporting bridge extending over the end thereof and 100 an integral exterior shoulder, a reflector supporting member engaging the said shoulder, and a metal lamp socket supported by the bridge.

4. The combination of a reflector or shade 105 of insulating material having a neck portion provided with an integral exterior shoulder, a reflector supporting member en-

gaging with said shoulder, and a cap covering the end of the neck portion and supported on the reflector supporting member.

5. The combination of a reflector or shade of insulating material having a neck portion provided with an integral exterior shoulder, a reflector supporting member engaging with said shoulder, and a cap covering the end of the neck portion and supported on 10 the reflector supporting member, the opening of said cap being sufficiently larger than the neck portion of the reflector to provide an opening between said cap and neck portion.
15. 6. The combination of a reflector or shade of insulating material having a neck portion

provided with an integral exterior shoulder, a reflector supporting member engaging with said shoulder, a socket supporting bridge extending over the end of the neck portion but not inclosing the same, a metal lamp socket attached to said bridge and of smaller cross-sectional area than the interior of the neck portion, and a cap covering the end of the neck portion of the reflector. 20 25

In testimony whereof, we have hereunto set our hands and affixed our seals:

EDWIN F. GUTH. [L. S.]
R. V. OWEN. [L. S.]
